CLAIM

The ornamental design for a tire, as shown and de-
scribed.

DESCRIPTION

FIG. 1 is a perspective view of a tire showing my new design, it being understood that the tread pattern is repeated throughout the circumference of the tire, as shown schematically by solid lines, the opposite side being substantially the same as that shown; and, FIG. 2 is a fragmentary front elevation view of the lower portion thereof.

FIG. 1

FIG. 2
